CLAIM

I claim the ornamental design for a container for an electronic device, as shown and described.

DESCRIPTION

FIG. 1 is a front elevational view of a container for an electronic device;

FIG. 2 is a bottom plan view of the container for an electronic device;

FIG. 3 is a rear elevational view of the container for an electronic device.

FIG. 4 is a right side plan view of the container for an electronic device;

FIG. 5 is a left side plan view of the container for an electronic device; and,

FIG. 6 is a top plan view of the container for an electronic device.
